UNITED STATES PATENT OFFICE.

LEWIS D. BLACKSHERE, OF CHARLESTON, WEST VIRGINIA, ASSIGNOR TO THE LIBBEY-
OWENS SHEET GLASS COMPANY, OF TOLEDO, OHIO, A CORPORATION OF OHIO.

BENDING-CHAMBER FIRE BOX.

Application filed March 16, 1925. Serial No. 15,827.

The present invention relates to sheet glass apparatus, and has particular reference to a type of apparatus wherein a sheet is initially drawn in a vertical plane and is bent over a deflecting member to a horizontal plane.

An important object of the invention is to provide apparatus of this nature including means for heating the sheet as it is being deflected from one plane to another.

10 A further object is to provide a sheet glass drawing apparatus wherein a sheet is continuously drawn from a source of molten glass, the said sheet being initially started in a vertical plane, after which it is bent over a 15 suitable deflecting member into a horizontal plane, said apparatus including means for radiating heat upon the sheet as it is bent to prevent breakage of the sheet during the deflecting movement thereof.

20 Still another object is to provide means for heating a sheet of glass which is being deflected from one plane to another by placing a heat radiating plate between that portion of the sheet being bent and suitable heating means.

Other objects and advantages of the invention will become apparent during the course of the following description.

The drawing shows a fragmentary vertical longitudinal section through a type of apparatus in which the invention may be used.

The type of machine illustrated is that disclosed in the Colburn Patent 1,248,809, granted Dec. 4, 1917, wherein a tank furnace 1 containing a source of molten glass is provided. The batch of ingredients used in the glass is introduced within the tank 1 at one end where they are subjected to an intense heat to melt and make homogeneous a mass of molten glass, after which the glass passes through the refining end. The numeral 3 designates a so-called goose-neck which connects the tank 1 and the draw-pot 4 which is supported upon the stools 5. The draw-pot 4 contains a pool of molten glass 6 which is relatively more shallow than the mass 10 within the tank. The sheet 7 is drawn from the source 8 in a vertical plane as is clearly shown. At a substantial distance from the sheet source 8 it is bent over a so-called bending roll 9 into a horizontal plane where it passes over an idler roll 10, draw table 11, and through an annealing leir which is not

shown. The bending roll 9 is usually 55 formed from some non-corrosive metal alloy such as nichrome or monel. Sheet edge engaging rolls 12, which are usually knurled, are provided at both ends of the sheet source or meniscus 8 to build up an edge by absorbing heat therefrom and retarding movement thereof which will hold the sheet to width after it has left its source 8. From the time the glass leaves the pool 6 until it reaches the bending roll 9 considerable heat has been 60 dissipated so that the sheet is relatively viscous and fairly well set. To overcome or prevent breakage or strains in the sheet as it passes over the bending member 9, it is advisable to apply heat to the sheet while it is 65 being bent. Ordinarily an open gas flame is applied directly to the sheet.

It is an aim of this invention to apply sufficient heat to the sheet being bent to facilitate bending thereof, but at the same time 75 the objectionable features encountered when playing a gas flame directly upon the sheet are overcome.

The numeral 13 designates a suitable heating element which may be in the nature 80 of a gas burner which is provided with a plurality of small apertures as is well understood. The burner 13 is contained within a compartment 14 separated from the compartment 15 by a baffle plate 16 having a 85 plurality of openings 17 formed therein. Positioned within the compartment 14 and arranged below the burner 13 is a radiation plate 18 which may be formed from carborundum or some other suitable material 90 which will absorb and radiate heat from the burner, whereby the heat may be radiated from the said plate upon the sheet to soften the same during the bending operation. An additional advantage of the radiated heat 95 treatment is that in the old process of open flame it was impossible to get an even uniform play of flame upon the sheet, whereas in the present instance the plate 18 will be heated to a uniform temperature throughout 100 its entire length, thus radiating an even uniform discharge of heat. An adjustable trap door or damper 19 is provided in the upper compartment 15 to take care of the products of combustion from the compartment 14.

105 Although, but a single burner 13 is disclosed in the drawing any number of burners may be utilized depending upon the inten-

sity of heat desired upon the glass at the point where it is being bent.

It is to be understood that the form of the invention herewith shown and described is to be taken as the preferred embodiment of the same, and that various changes in the shape, size and arrangement of parts may be resorted to without departing from the spirit of the invention or the scope of the subjoined claim.

Another point to be remembered is that the heat used to soften the glass is localized and is not capable of heating more of the sheet than is necessary. In the case of open flames, the flames from the burners follow along with the sheet in the direction of draw and keep the glass hotter for a longer period than is necessary, thus sometimes permitting

other parts of the apparatus contacting with the sheet to form impressions therein.

20

Claim:

In sheet glass apparatus, means for drawing a sheet from a mass of molten glass, means for deflecting the sheet from one plane to another, a gas burner arranged in proximity to the sheet where it is being bent, and a radiating plate between the burner and the sheet, said plate being spaced from but parallel to a plane tangent to the curved path traversed by the sheet while the sheet is being bent from a vertical into a horizontal plane.

Signed at Charleston, in the county of Kanawha, and State of West Virginia, this 9th day of March, 1925.

LEWIS D. BLACKSHERE.
